UNITED STATES PATENT OFFICE.

OTIS R. HASTY, OF ELGIN, ILLINOIS.

SHOE-SHINING CHAIR.

2,225,811.

Specification of Letters Patent. Patented May 15, 1917.

Application filed August 22, 1913. Serial No. 117,181.

To all whom it may concern:

Be it known that I, OTIS R. HASTY, a citizen of the United States, residing at Elgin, in the county of Kane and State of Illinois, have invented certain new and useful Improvements in Shoe-Shining Chairs, of which the following is a specification.

The invention has for its object the provision in a shoe shining chair of means for raising and lowering the seat and, together therewith and independently thereof, the foot rest in order to facilitate the mounting of the customer to the seat and also to accommodate the working height to the convenience of the workman.

In earlier times the customer stood or sat with his foot upon a rest arranged substantially at the ground level, thus necessitating the kneeling of the workman. For the convenience of the latter the position of the customer was elevated to bring the foot rest to a height of three feet or such a matter above the floor, thus entailing the employment of a foot rest on a tall standard, which foot rest must be used as a step in mounting to or descending from the seat. This sort of foot-rest is not only a fruitful source of injury by reason of its catching the overcoats of men and the skirts of ladies, or by the slipping of the foot therefrom, but it is a constant cause of embarrassment to the latter sex and ladies are discouraged from patronizing shoe shining establishments by the existence of the conditions here pointed out.

By the present invention, the customer seats himself in the chair at a moderate elevation, the height of the foot rest is initially adjusted to suit the customer's length of limb, and then, by the manipulation of a certain lever, the seat, foot rest and the customer are bodily elevated to a position to suit the workman's convenience. When the work is completed, the clutch is again operated and the seat and foot rest, with the customer are gently lowered until the foot rest is substantially flush with the floor, and the customer moves away without having had to climb onto or descend from a high perch by the precarious means of narrow foot pieces on the top of tall standards. All exertion is thus avoided, danger is obviated and nervousness or embarrassment entirely done away with.

In order that the invention may be readily

understood and the manner of its utilization made clear, a preferred embodiment of the same is set forth in the accompanying drawings and in the following detailed description predicated thereon. Obviously, the invention is susceptible of embodiment in other and varied forms without sacrifice of its material advantages, wherefore the drawing and description are to be taken in an illustrative and not in an unnecessarily limiting sense. In the drawing—

Fig. 1 is a vertical section through a shoe shining chair embodying my invention;

Fig. 2 is a detail sectional view of the foot rest and its standard;

Fig. 3 is a horizontal section on the line 3—3 of Fig. 2;

Fig. 4 is a front elevation of a battery of shoe shining chairs characterized by the present invention;

Fig. 5 is a horizontal section on the line 5—5 of Fig. 1;

Fig. 6 is a rear elevation of the raising and lowering mechanism;

Fig. 7 is a detail sectional view showing the detent for holding the seat in raised position;

Fig. 8 is a transverse section on the line 8—8 of Fig. 6;

Fig. 9 is a detail view in side elevation illustrating the detent mechanism and also the means for automatically stopping the elevating and lowering mechanism; and

Figs. 10 and 11 are diagrammatic views illustrating successive steps in the operation of the automatic means for stopping the raising and lowering mechanism.

Having reference to the particular embodiment of the invention illustrated, the floor or platform is indicated at 11 with a raised portion 12, the latter having a height above the platform corresponding substantially to the height of an ordinary chair. In the space beneath the platform 11, 12 is vertically mounted the foot rest standard 13 which receives telescopically in its upper portion the stem 14 of the foot rest 15. The stem 14 in its lower portion is flattened on one side and provided with the ratchet toothed rack 16 with which engages a nose 17 of a lever fulcrumed at 18, the other arm of the lever being under the influence of the spring 19. Upon a suitable support is arranged a bracket 20 the outer end of which 21

is disposed adjacent the lower arm of the lever and is adapted to hold the nose 17 of the lever out of engagement with the rack when the parts are in the position shown in Fig. 1.

5 Likewise vertically disposed within the space beneath the platform 11-12 is the seat standard 21 carrying upon its upper end the chair seat 22. The standard 21 is provided along its rear face with a toothed rack 23 and at its lower end is rigidly cross-connected by means of the yoke 24 with the lower end of the foot rest standard 13.

As thus far described it will be observed 15 that the chair seat 22 and the foot rest 15 occupy positions, the former immediately above the raised portion 12 of the platform and the foot rest immediately above the floor level of the platform at 11. And it is 20 this condition of affairs which the customer encounters upon entering the shoe shining shop. Standing upon the platform 11 the foot rest 15 is substantially flush with the floor and, seating himself in the chair seat 25 22 his feet readily are accommodated on the foot rest 15. When seated in the chair, the foot rest 15 may be adjusted vertically to suit the length of limb of the customer by the workman grasping the foot rest and lifting the same, the nose 17 of the lever riding over the ratchet teeth and engaging the same when the foot rest 15 is released.

The provision made for raising and lowering the seat 22, the foot rest 15 and the 35 customer bodily will now be explained: A motor is indicated at 25 from which a drive belt 26 leads to the pulley 27 on the driven shaft 28. This shaft carries a sprocket 29 and a belt pulley 30. The sprocket 29 is connected by the sprocket 31 with a companion sprocket 32 loosely mounted on the countershaft 33 while the belt pulley 30 is connected by a cross belt 34 with a belt pulley 35, also loosely mounted upon the countershaft 33. The adjacent faces of the hubs of the sprocket 32 and the belt pulley 35 are concaved for coaction with the double face friction clutch 36, 37 keyed to the countershaft 33 and shiftable 40 longitudinally thereon by means of the clutch actuating lever 38 fulcrumed at 39 and connected by a link 40 with a clutch control lever 41, the handle 42 of which projects through the wall 43 of the structure. 45 Upon the countershaft 33 is mounted a pinion 44 in mesh with a larger pinion 45 fixed upon a transmission shaft 46 which carries another small pinion 47 which is in mesh with the larger pinion 48 on the second 50 transmission shaft 49, which latter shaft also carries a pinion 50 arranged in mesh with the rack 23 on the standard 21.

It should now be obvious that if the clutch control lever 42 be moved to the right the 55 clutch 37 will be brought into frictional en-

gagement with and effect a driving of the countershaft 33 by means of the sprocket 32, thereby vitalizing the train of gearing and causing the seat standard 21 with the seat 22 to move upward, carrying with it 70 through the cross connection 24 the foot rest standard 13 and the foot rest 15. A shifting of the clutch control lever 42 to the left will, on the contrary, move the clutch member 36 into engagement with the pulley 35 75 and cause the driving of the shaft 33 in the opposite direction and, through the train, will cause the lowering of the seat standard 21 and the seat 22, carrying with them at the same time the foot rest standard 13 and 80 the foot rest 15. In order to automatically stop the raising and lowering mechanism as the seat reaches its upper and lower extreme positions, means are provided as follows: On the side of the seat standard 21 85 at 51 is arranged a cam which as the seat standard descends impinges against clutch actuating lever 38, as indicated in Fig. 9, and shifts the same to neutral position. In order to stop the mechanism when the seat 90 and foot rest reach their extreme lower position, a stop rod 52 is slidably mounted within the bracket 53 and is upwardly pressed by means of the spring 54. The lower end of the stop rod 52 is angularly 95 bent as indicated at 55 and extends beneath and in alignment with the standard 21. The upper end of the stop rod 52 carries a wedge like cam 56, the inclined face of which is adapted to bear against the opposite side of 100 the clutch actuating lever 38 when the descending standard 21 shall have engaged the angular portion 55 of the stop rod and push the same downwardly against the tension of the spring 54.

In order to positively support the seat standard 21 in elevated position, said seat standard is provided with a ratchet toothed plate 57 adjacent the cam 51, the teeth of which ratchet are adapted to be engaged 110 by the teeth of a spring detent 58 slidably mounted in the block 59 and held against the standard 21 by the yielding force of the spring 60. The outer end of the detent 58 115 is provided with a slot 61 within which engages a pin 62 carried by the clutch control lever 41. It will thus be seen that upon the actuation of the clutch control lever 41 to the left to effect the lowering of the elevated seat, the detent 58 will be first 120 drawn out of engagement with the ratchet teeth 27 before the clutch becomes effective, thus releasing the positive engaging means and permitting the seat and its standard to descend under the control of the pulley 35. 125 The actuation of the clutch control lever 41 in the opposite direction to effect the raising of the standard will not, however, by reason of the slot and pin connection, affect in any way the spring detent.

It is thought that the advantages of the invention will have been made clear. The customer takes his seat in the chair and places his feet upon the foot rest 15, not being compelled to utilize the latter as a means for mounting to the chair, the relative height of the two being proportioned to the length of limbs of the average person. The foot rest having been adjusted, as necessary, for the comfort of a short person, the clutch control lever 41 by means of its handle 42 is shifted to the right and the seat and foot rest are elevated in unison until the customer occupies a position which is now usual, that is to say, elevated at a considerable distance above the platform 11. When the job is completed, the control lever 41 by its handle 42 is moved to the left and the train of gearing is again brought into play in the reverse direction to lower the chair and its occupant, the foot rest descending at the same time and the customer being enabled to rise from his seat without having to climb down and over upstanding foot rest standards. The arrangement is a simple and efficient one, and as nearly automatic as it is practicable to be made reserving a control over the same to the operator. I am aware that it is old in barber chairs, dental chairs and the like to elevate the chair and the patient bodily, but in the present situation novel conditions are met and provided for, thus eliminating from the shoe-shining parlor the objectionable features which have been well recognized and appreciated but for the alleviation of which no means have hitherto been suggested.

I claim:

1. In a shoe shining chair, the combination of a foot rest normally substantially at the floor level, a seat normally at a height corresponding to the foot rest, and mechanism to elevate the seat and foot rest with the customer to a position with the shoes conveniently accessible to the workman and to thereafter restore the same to normal conditions, comprising a toothed seat standard, a pinion meshing therewith, a motor driven shaft, a train of gearing connecting the shaft and pinion, means to vitalize said train, means to reverse the train movement, and a connection between the seat standard and the foot rest whereby they are elevated and lowered jointly.
2. In a shoe shining chair, a platform providing an under space, a foot rest standard vertically disposed within the space with the upper end projecting slightly above the floor level, a foot rest thereon, a seat standard vertically disposed within the space with its upper end projecting above the platform, a seat on the latter standard at an elevation appropriately corresponding to that of the foot rest, the seat and foot rest standards cross connected together, and mechanism for raising and lowering the seat and foot rest jointly.
3. In a shoe shining chair, a platform providing an under space, a foot rest standard vertically disposed within the space with the upper end projecting slightly above the floor level, a foot rest thereon, a seat standard likewise vertically disposed within the space with its upper end projecting above the platform, a seat on the latter standard at an elevation appropriately corresponding to that of the foot rest, the seat and foot rest standards cross connected together, and mechanism for raising and lowering the seat and foot rest jointly, and means to automatically stop the raising and lowering mechanism as the seat approaches its upper and lower extreme positions.
4. In a shoe shining chair, a platform providing an under space, a foot rest standard vertically disposed within the space with the upper end projecting slightly above the floor level, a foot rest thereon, a seat standard likewise vertically disposed within the space with its upper end projecting above the platform, a seat on the latter standard at an elevation appropriately corresponding to that of the foot rest, the seat and foot rest standards cross connected together, the seat standard bearing a toothed rack, a pinion meshing therewith, a motor-driven shaft, a pair of pulleys thereon, a countershaft, a pair of loose pulleys thereon, driving connections between the pulleys on the driven and counter shaft, a double faced clutch on the countershaft arranged to engage the two loose pulleys alternatively, a train of gearing connecting the counter shaft and pinion, and means to actuate the clutch whereby to raise or lower the seat and foot rest jointly.
5. In a shoe shining chair, a platform providing an under space, a foot rest standard vertically disposed within the space with the upper end projecting slightly above the floor level, a foot rest thereon, a seat standard likewise vertically disposed within the space with its upper end projecting above the platform, a seat on the latter standard at an elevation appropriately corresponding to that of the foot rest, the seat and foot rest standards cross connected together, the seat standard bearing a toothed rack, a pinion meshing therewith, a motor-driven shaft, a pair of pulleys thereon, a countershaft, a pair of loose pulleys thereon, driving connections between the pulleys on the driven and countershaft, a double faced clutch on the countershaft arranged to engage the two loose pulleys alternatively, a train of gearing connecting the countershaft and pinion, and means to actuate the clutch whereby to raise or lower the seat and footrest jointly, and means to shift the clutch to neutral position when the

seat approaches its extreme upper position and likewise when it reaches its extreme lower position.

6. In a shoe shining chair, a platform providing an under space, a foot rest standard vertically disposed within the space with the upper end projecting slightly above the floor level, a foot rest thereon, a seat standard likewise vertically disposed within the space with its upper end projecting above the platform, a seat on the latter standard at an elevation appropriately corresponding to that of the foot rest, the seat and foot rest standards cross connected together, the seat standard bearing a toothed rack, a pinion meshing therewith, a motor-driven shaft, a pair of pulleys thereon, a countershaft, a pair of loose pulleys thereon, driving connections between the pulleys on the driven and countershaft, a double faced clutch on the countershaft arranged to engage the two loose pulleys alternatively, a train of gearing connecting the countershaft and pinion, and means to actuate the clutch whereby to raise or lower the seat and foot rest jointly, and means to shift the clutch to neutral position when the seat approaches its extreme upper position and likewise when it reaches its extreme lower position, said means comprising cams moving with the seat standard and arranged to act on the clutch operating means.

7. In a shoe shining chair, a platform providing an under space, a foot rest standard vertically disposed within the space with the upper end projecting slightly above the floor level, a foot rest thereon, a seat standard likewise vertically disposed within the space with its upper end projecting above the platform, a seat on the latter standard at an elevation appropriately corresponding to that of the foot rest, the seat and foot rest standards cross connected together, and mechanism for raising and lowering the seat and foot rest jointly, a detent arranged to engage and hold the

seat standard in elevated position, and a connection between the clutch-actuating means and the detent whereby to automatically retract the same as the clutch is thrown into operation.

8. In a shoe shining chair, a platform providing an under space, a foot rest standard vertically disposed within the space with the upper end projecting slightly above the floor level, a foot rest thereon, a seat standard likewise vertically disposed within the space with its upper end projecting above the platform, a seat on the latter standard at an elevation appropriately corresponding to that of the foot rest, the seat and foot rest standards cross connected together, the seat standard bearing a toothed rack, a pinion meshing therewith, a motor-driven shaft, a countershaft, a pair of loose pulleys thereon, driving connection between the pulleys on the countershaft and the driven shaft, a double-faced clutch on the countershaft arranged to engage the two loose pulleys alternatively, a train of gearing connecting the countershaft and pinion, means to actuate the clutch whereby to raise or lower the seat and foot rest jointly, means to shift the clutch to neutral position when the seat approaches its extreme upper position and likewise when it approaches its extreme lower position, said means comprising cams moving with the seat standard and arranged to act on the clutch-actuating means, a detent arranged to engage and hold the seat standard in elevated position, and a connection between the clutch actuating means and detent whereby to automatically retract the detent as the clutch is thrown into operation.

In testimony whereof I have hereunto signed my name in the presence of two subscribing witnesses.

OTIS R. HASTY.
